UNITED STATES PATENT OFFICE.

BISMARCK B. BRODFUEHRER, OF CINCINNATI, OHIO, ASSIGNOR TO MARKEM MACHINE COMPANY, OF BOSTON, MASSACHUSETTS, A CORPORATION OF MASSACHUSETTS.

MARKING MACHINE.

Application filed February 7, 1927. Serial No. 166,339.

This invention relates to marking machines and particularly to marking machines of the type which are commonly used for marking the linings of shoes.

5 In the manufacture of shoes it is customary to mark on the lining some identifying figures or letters. Such identifying marks usually include a number indicating the size of the shoe and also a stock number 10 or style number and a case number. Some machines, such for instance as those illustrated in Patents No. 1,131,865, March 16th, 1915 and No. 1,131,866, March 16th, 1915 are constructed to print the desired identifying numbers at the same time and arranged in two or more lines, the number 15 on one line indicating the stock number or style number, the number on another line indicating the size of the shoe and the number 20 on still another line indicating the case number.

These identifying numbers are usually placed on the inside of the shoe and there has recently grown up a method of marking 25 shoes which is termed "window marking." In accordance with this method the lining of the shoe has an opening formed therein at the place where the marking is to be imprinted and the identifying marks are made 30 on a separate piece of cloth or leather which is sewed to the outer face of the lining in position so that the marking will be visible through the opening in the lining. When the shoe is completed the cloth or leather 35 having the mark thereon is located between the lining and the upper of the shoe and the identifying marks are visible from the interior of the shoe through the opening in the lining. Hence the term "window marking."

40 This method of marking gives the shoe an attractive appearance because the peripheral edges of the opening through the lining and the line of stitching circum- 45 scribing this peripheral edge forms a sort of border for the marks. This method of marking, however, involves the operation of cutting a hole through the lining and then sewing the cloth to the outer face of the 50 lining over the hole in addition to the operation of imprinting the identifying marks on the cloth.

It is one of the objects of my invention to provide an improvement in the machines

such as shown in the above-mentioned Patents No. 1,131,865 and No. 1,131,866 by which an imprint may be made directly on the lining of the shoe which has all the appearance of "window marking" but which is accomplished without the necessity of cutting the hole in the lining and sewing over the hole the cloth bearing the mark. In accordance with my invention the desired marking having the appearance of "window marking" is stamped directly on the lining of the shoe at one operation thus producing a mark which is fully as attractive as "window marking" but which involves in its making very much less labor.

55 In order to give an understanding of the invention I have illustrated in the drawings a selected embodiment thereof which will now be described after which the novel features will be pointed out in the appended 60 claims.

70 Fig. 1 is a fragmentary view showing the printing head and work support of a machine such as illustrated in Patent No. 1,131,865 and embodying my invention;

75 Fig. 2 is an enlarged under side view of 80 the printing head;

Fig. 3 is a view illustrating the character of the mark which is made by the marking machine;

85 Fig. 4 is a perspective view of the type plate by which the border line is marked;

90 Fig. 5 is a perspective view of the type plate which carries the type for printing the stock number and the size number;

95 Fig. 6 is an enlarged section on the line 6-6 Fig. 2 with the type wheels omitted;

100 Fig. 7 is a section through the type plates on the line 7-7, Fig. 6 and illustrating a portion of one of the type wheels.

105 Since the present invention relates simply to the construction of the type plates which are associated with the printing head of a marking machine of the general type shown in Patent No. 1,131,865 I have not deemed it necessary to illustrate herein the entire machine but have shown only a sufficient portion thereof to enable my present invention to be understood.

110 In the drawings 1 indicates generally the printing head of a printing machine and 2 is the work support or platen, the latter being supported by the frame 3. The printing head 1 is mounted on an arm 4 which

is given a movement to carry the printing head 1 toward and from the platen 2 as usual in printing machines of this type.

This printing head 1 is formed with two side members 5 between which are mounted a plurality of type wheels 6. Each type wheel is provided on its periphery with radial type-bearing projections 7 that have type characters 8 formed on the ends thereof. These type wheels are capable of being individually set or adjusted as usual in marking machines of this type so that the type wheels can be set to print any desired number.

Associated with the type wheels is a type carrier 9 which carries individual removable type members, all as shown in said Patent No. 1,131,866. In the embodiment of the invention shown in Fig. 5 the type carrier 9 is formed with two type-carrying portions 10 and 11, the type-carrying portion 10 supporting a plurality of type members 12 and the type-carrying portion 11 supporting another set of type members 13. These type-carrying portions 10 and 11 are formed on their outer edges with notches 14 in which the type members are received and each type member comprises a body portion 15 carrying the type character 16 and a U-shaped shank portion 17 which embraces the portion 10 or 11 of the type carrier 9 and is received in one of the notches 14.

These type members 12 and 13 are removably held in place by means of retaining bars 18 which are pivoted to the type carrier at one end as shown at 19. When the retaining bars are swung upwardly about their pivots the individual type members 12 and 13 may be placed on the type character in an order or sequence to print any desired number and when the type members have been properly set they are locked in position by swinging the retaining bars 18 downwardly into the position shown in Fig. 5. This construction is very similar to that shown in Patent No. 1,131,866 except in said patent the type carrier has a single type-carrying portion only while in Fig. 5 it has two type-carrying portions.

This type carrier is mounted in a holder which is pivotally connected to the printing head and which comprises the two side members 20 which have grooves 21 to receive the ribs 22 on the ends of the type carrier 9. This holder is pivoted to the printing head at 23 and when it is in its operative position as shown in Figs. 1 and 7 the type-carrying projections 7 of the type wheels which are in operative position to make a printed impression will be received in the space 24 between the type-carrying portions 10, 11 and will be between the two rows of type members 12 and 13. With this arrangement each printing operation will make a three-line printed impression, one line being made

by the row of type members 12, another line being made by the type characters on the type projections 7 which are in operative position, and the third line being made by the row of type members 13.

As shown in the drawings the type members of the printing head are set so that the top line of the printed impression will be the number "35241," the middle line will be the number "90198165," while the bottom line will be the number "35142."

In order to make a printed impression having the appearance of the "window marking," that is, a printed impression in which the identifying marks have a border around them, I have provided herein an additional type character or type plate which may be assembled with the type carrier 9 and which is provided with a printing portion that surrounds the type members 12 and 13 and also the type projections of the type wheel that are in printing position. Such a type plate is shown in Fig. 4 and it comprises a body portion 25 having an opening 26 therein of a size to receive the type members 12 and 13 and also those type projections 7 of the type wheels which are in printing positions, said body being formed with an impression portion 27 immediately surrounding the border 26. This impression portion 27 which is raised somewhat may have its impression surface cut or formed to make any desired border around the printed impression which is made by the type wheels 6 and the type members 12 and 13. The raised surface 27 may be shaped to print a border which simulates the "window marking" as shown in Fig. 3 or it may have letters or words thereon so that the border portion will contain the name of the maker of the shoe or some other information.

In the construction shown in Fig. 4 this raised portion 27 is formed with a ridge 28 which prints on the lining 29 a line 30 that simulates the peripheral edge of the opening in the lining when it bears the "window marking" and it is also formed with raised portions 31 which print the dotted line 32 that simulates the line of stitching of the "window marking." The additional type plate 25 is formed at its ends with arms 33. When said type plate is in operative position it overlies the type carrier 9 and the arms 33 fit into the space 24 between the type-bearing portions 10 and 11. Said arms 33 are formed at their ends with offset ribs 34 which are aligned with the ribs 22 when the type plate 25 is in its operative position and thus the assembled plate 25 and type carrier 9 may be inserted into or removed from the supporting groove 21 of the holder 20 as a unit.

The assembled plate and type carrier are retained in proper position in the holder 20

by means of positioning pins 35 which are adapted to enter indentations 36 formed in the ribs 34 of the type plate 25. These pins 35 are controlled by levers 37 pivoted to the holder 20 at 38, each lever having a forked end to engage in the groove 39 of the positioning pin and being acted on by a spring 40 which operates to yieldingly hold the pins in their operative position.

10 I claim:

1. In a marking machine, the combination with a printing head having adjustable type wheels each provided with a plurality of type-bearing projections, of a holder carried by said head and provided with opposed grooves, a detachable carrier having its ends removably received in said grooves, two rows of type members removably sustained by the type carrier and situated on opposite sides of the row of type-bearing projections on the type wheels which are in position to make a printed impression, a type plate separable from the type carrier and having its ends received in said grooves and also being interlocked with the type carrier, said type plate being provided with a printing portion which surrounds both the type members on the type carrier and said row of type-bearing projections.

2. In a marking machine, the combination with a printing head having adjustable type wheels each provided with type-bearing projections, of a holder, a type carrier detachably supported by the holder, a row of type members removably sustained by the type carrier and situated closely adjacent the type-bearing projections which are in position to make a printed impression, a type plate separable from the type carrier but interlocked therewith and held in posi-

tion thereby, said type plate being provided with a printing portion which surrounds both the type members and said row of type-bearing projections.

3. In a marking machine, the combination 45 with a printing head having adjustable type wheels each having type-bearing projections, of a holder carried by said head and provided with opposed grooves, a type carrier supported in said grooves, type members 50 removably supported by said carrier and situated closely adjacent the type-bearing projections which are in position to make a printed impression, a type plate separable from the type carrier, and also supported 55 in said grooves, said type plate having a printing portion which surrounds both the type members on the type carrier and said row of type-bearing projections on the type wheel.

4. In a marking machine, the combination 60 with a printing head having adjustable type wheels each provided with type-bearing projections, of a holder supported by the printing head and provided with opposed grooves, 65 a type carrier supported in said grooves and having a central opening extending longitudinally thereof, type members removably supported by the type carrier, and a type plate separable from the type carrier and 70 having arms on its ends which are received in the opening in the type carrier, the ends of the arms being received in said grooves, said type plate having a printing portion 75 which surrounds both the type members and the type-supporting projections.

In testimony whereof, I have signed my name to this specification.

BISMARCK B. BRODFUEHRER.
